UNITED STATES PATENT OFFICE.

PERRY OLMSTED, OF LOS ANGELES, CALIFORNIA.

DRAFTING INSTRUMENT.

1,143,431.

Specification of Letters Patent. Patented June 15, 1915.

Application filed January 24, 1914. Serial No. 814,091.

To all whom it may concern:

Be it known that I, PERRY OLMSTED, a citizen of the United States, residing at Los Angeles, in the county of Los Angeles and State of California, have invented a new and useful Drafting Instrument, of which the following is a specification.

This invention is a drafting instrument.

One of the objects of the invention is to provide a single drafting instrument adapted to be used in drawing horizontal, vertical, and angular lines and for taking measures in all directions and from any desired point, on a drafting board.

Another object is to provide a drafting instrument of this type which will be easier and more convenient for a draftsman to handle than the ordinary T square, triangle, and ruler used for the purpose for which this invention is designed, and by means of which greater accuracy and speed may be attained than by the instruments now in use.

In the accompanying drawings forming part of this specification,—Figure 1 is a plan view of my invention, shown in full lines in position for drawing horizontal and vertical lines and for taking horizontal and vertical measures, and in dotted lines in position for drawing angular lines and for taking angular measures. Fig. 2 is a sectional view of a detail of construction taken on the line x^2-x^2 of Fig. 1. Fig. 3 is a sectional view of a detail of construction taken on line x^3-x^3 , of Fig. 1. Fig. 4 is a transverse sectional view of my invention taken on line x^4-x^4 of Fig. 1.

Referring to the structure of my invention, 1 indicates a rod extending across a drawing board 2 near the left edge thereof and parallel to said edge, which rod is slidably mounted in detachable clamp brackets 3, clamped respectively by screws 4 to the edge of the board adjacent the draftsman and the edge opposite to said edge. A set screw 5 is located in one of the brackets 3 which is adapted to engage the rod 1 to hold it against sliding and turning. A sliding frame 6 comprising upper member 7 and lower member 8 is slidably mounted upon rod 1 by means of hangers 9 forming part of the upper frame member 7 through which hangers said rod extends. A disk 10 is formed on the lower frame member 8, upon which disk rests a disk 11, formed on the upper frame member 7. A screw 12 extends through said disks, and a butterfly nut 13

screws on the upper end of said screw and engages the disk 11, whereby the lower frame member 8 is swiveled to the upper frame member 7. The disk 10 is larger in diameter than the disk 11 and is provided with a scale 14 of angular degrees. The disk 11 is provided with an arrow 15 pointing to the scale 14 which is adapted to point to the character indicating the degree of the angle at which the upper disk 10 is turned with relation to the disk 11. A rod 16 forming part of the frame member 8 is so located on said frame member as to rest close to the board 2. A coupling 17 is secured to the rod 16 near one end thereof, and a coupling 18 is slidably mounted upon said rod, to which couplings are pivoted the ends of the levers 20 and 21 at one end of the lazy tongs 25. The ends of the levers 29 and 30 at the other end of the lazy tongs are pivoted respectively at 31 and 32 to a measuring element 35 and to a sliding block 36, slidably mounted in guide 37 secured to said element. The measuring element through the lazy tongs 25 moves with the frame 6. The guide 37 covers the pivot connections 31 and 32 of the levers 29 and 30 so that they will not be in the way of the draftsman using the instrument. The measuring element 35 is provided with straight edges 40 and 41 against which a pencil or pen is adapted to be placed to draw straight lines. Scales 42 and 43 are provided along the edges 40 and 41 respectively by means of which measures may be taken. A scale 45 is provided along the rod 1 for measuring distances at which it is desired to move the element 35 vertically, whereby vertical distances may be measured by said element. A set screw 50 extends through one of the hangers 9 and engages the rod 1, whereby the frame 6 may be secured to the rod 1 in any position along the rod.

The operation of my invention is as follows: As illustrated in full lines in the drawing, the angle at which the measuring element 35 rests is zero, which is indicated by the registration of the arrow 15 on disk 11 with 0 of the scale 14 on disk 10. In this position of the measuring element, horizontal lines may be drawn along the edges 41 and vertical lines may be drawn along the edge 40 of said element, and horizontal measures may be taken with the scale 43 and vertical measures may be taken with the scale 42. The sliding coupling 18 and the

sliding block 36 permit the levers of the lazy tongs 25 to be brought together or drawn apart, so that the measuring element 35 may be moved in the direction of the axis 5 of extension and contraction of said lazy tongs. If it be desired to draw a long, horizontal line, the element 35 and lazy tongs 25 are maintained in the position shown in full lines in Fig. 1 of the drawing, 10 i. e. with the arrow 15 on disk 11 pointing to 0 on disk 10, in which position the axis of extension and contraction of the lazy tongs is in a horizontal direction which directs the movement of the element 35 horizontally. A pencil or pen may be placed 15 against either edge 41 and the element 35 moved in a horizontal direction for a distance corresponding to the length of the desired line. If it be desired to draw angular lines or to take angular measures, the 20 nut 13 is loosened and the lower frame member 8, lazy tongs 25, and element 35 swung to the desired angle and are clamped in such position by tightening nut 13, as illustrated 25 in dotted lines in Fig. 1 of the drawing. Angular lines may be drawn and angular measures may be taken with the element 35 in angular position, in the same manner as when the element 35 is in a horizontal position. For example, when the element 35 30 is at an angle of 30° , angular lines of 30° may be drawn along the edges 41 of element

35, and by moving the element in the direction of the axis of extension and contraction of the lazy tongs 25, (which in this position of element 35 is at an angle of 30° also) long lines at an angle of 30° may be drawn, and measures along lines of 30° may be taken with scales 43, while lines of 60° may be drawn along the edge 40, and 35 measures along lines of 60° may be taken with scale 42. Vertical measures may be taken above and below the element 35 and scale 42, by moving the frame 6 along the rod 1 until the hanger 9 adjacent the scale 40 40 registers with the desired measure on said scale. 45

What I claim is:

A drafting instrument comprising a support adapted to be attached to a drawing board, a frame comprising two members, one member being mounted upon said support, the other member being swiveled to said first member, a measuring element, and lazy tongs connecting said second frame member to said measuring element. 50

In testimony whereof, I have hereunto set my hand at Los Angeles, California, this 16th day of January, 1914.

PERRY OLMSTED.

In presence of—

GEORGE T. HACKLEY,
LORRAINE E. DURROW.
